[57] CLAIM

The ornamental design for a delayed action dosage unit for releasing medicaments or the like in ruminants, as shown and described.

DESCRIPTION

FIG. 1 is a side elevational view of a delayed action dosage unit for releasing medicaments or the like in ruminants showing my new design;

FIG. 2 is a perspective view thereof;

FIG. 3 is a bottom plan view thereof; and

FIG. 4 is a top plan view thereof.
